TUBE ADAPTER FOR NASAL INTUBATION

Edward J. Hill, 1660 Lochridge, Bloomfield Hills, Mich.

Filed Sept. 18, 1961, Ser. No. 66,742

Term of patent 14 years

(Cl. D83—1)

FIG. 1 is a front elevational view of a tube adapter for nasal intubation embodying the new design;

FIG. 2 is a rear elevational view; and

FIG. 3 is a side elevational view.

FIG. 2 is stippled to represent a contrast of material in respect to that of FIG. 1.

I claim:

The ornamental design for a tube adapter for nasal intubation, substantially as shown and described.
